UNITED STATES PATENT OFFICE.

LEWIS A. WILSON, OF NORTHEAST HARBOR, MAINE.

RULE.

No. 798,721.

Specification of Letters Patent.

Patented Sept. 5, 1905.

Application filed March 24, 1905. Serial No. 251,851.

To all whom it may concern:

Be it known that I, LEWIS A. WILSON, a citizen of the United States, residing at Northeast Harbor, in the county of Hancock and State of 5 Maine, have invented certain new and useful Improvements in Rules, of which the following is a specification.

This invention relates to improvements in T-square rules of that type embodying, essentially, a rule having an adjustable head with suitable means for determining the angle of adjustment of the head with relation to the rule.

The invention resides, essentially, in the 15 provision of a device of novel construction whereby the length of the rule may be extended, so that the same will be equalized for larger or smaller work, according to various conditions arising in actual use.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, 30 still the preferred embodiment is shown on the accompanying drawings, in which --

Figure 1 is a plan view of a rule embodying the invention, the adjustable section thereof being extended a short distance. Fig. 2 is a 35 transverse sectional view on the line 2-2 of Fig. 1, showing more clearly the connection between the sections of the rule. Fig. 3 is a broken perspective view, the adjustable rule-sections being shown partly projected from 40 the body-section.

Corresponding and like parts are referred to in the following description and indicated in all the views of the drawings by the same reference characters.

Referring to the drawings, the letter A designates the rule, and the letter B the head thereof, the two forming an ordinary T-square. The rule A is pivotally secured to the head B, a suitable set-screw 1 being provided to secure the parts together and admit of adjustment of the parts at a predetermined angle with relation to each other. The upper side of the head B is provided with a suitable arc-scale 2, with which a pointer 3, carried by the adjacent end of the rule A, is

adapted to coöperate to indicate the angle of adjustment of the rule to the head.

The rule A consists of a relatively stationary body-section 4 and adjustable sliding sections 5 at opposite longitudinal edges thereof and 60 peculiarly attached to the body 4. The sections 5 are arranged for longitudinal movement at the opposite sides of the body 4, and the said sections, as well as the body, are provided with scale-marks, which may be inches, 65 centimeters, or any other suitable scale measurements, the parts 4 and 5 having the edge portions in alinement. Thus when the sections 5 by slidable movement are projected from the body 4 said sections will form a continuation of the ruling edges of the body, so that lines of greater length may be made in the customary manner. A lug 6 projects outwardly from the sections 5 at a point between the ends thereof and forms a finger 70 piece for each section, as will be readily apparent.

The construction of the body 4 and the sections 5 is peculiar in order to form an interlocking connection between these parts which will 80 be substantial and practical. Since each of the sections 5 is mounted in the same manner, only one will be described. Projecting rearwardly from a longitudinal edge of the section 5 is a flange 7, the upper side of which is provided with a longitudinal groove 8. This flange is received in a recess 9 in a side of the ruler A, said recess being provided longitudinally thereof with a downwardly-extending rib or tongue 10. The tongue 10 is received 90 in the groove 8 of the flange 7, so that the flange 7 forms an interlocking connection between the body of the section 5 and the body 4 of the ruler, admitting, however, of free slidable movement of the section 5, in order 95 to adjust the same and increase the length of the ruling device, as above premised. A longitudinal tongue 11 projects from the rear side of the body of the section 5, and said tongue operates in a groove or kerf 12 in the body-section 4 of the ruler, the groove 12 aforesaid being located just beneath the recess 9 above described. The outer side of the body of each section 5 slants, so as to form a beveled edge for the ruler, a conventional and desirable construction, as will be found in most rulers at present in use.

If necessary, the body A of the ruler, in order to facilitate the formation of the interlocking recess, kerfs, and tongues, may be 110

made in two parts *a* and *b*, said parts *a* and *b* being secured together by screws or finished fastenings of any kind, as most desirable.

An essential feature of the invention is the provision of the rule portions at either side of the part A, the same being divided into convenient scales, in order to be useful and very convenient, and having all the advantages of the scale-rules at present in common use. Further, the device combines the drafting-rule and T-square, and the draftsman's scale is always before him, saving much time and annoyance in his work.

Having thus described the invention, what is claimed as new is—

A rule of the type described embodying a body-section provided with a recess longitudinally of a side thereof, a relatively movable

section having a longitudinal flange projected rearwardly therefrom and formed with a longitudinal groove, said flange being received in the recess of the rule-body aforesaid, a longitudinal tongue projecting from a side of the recess in the body-section into the groove of the flange and interlocking therewith, and a longitudinal tongue projecting rearwardly from the movable section, the body-section having a longitudinal groove beneath the longitudinal recess before mentioned to receive the longitudinal tongue of the movable section. 20 25 30

In testimony whereof I affix my signature in presence of two witnesses.

LEWIS A. WILSON, [L. S.]
